(57) **CLAIM**

The ornamental design for a compressor enclosure, as shown and described.

DESCRIPTION

FIG. 1 is a front perspective view of a compressor enclosure in accordance with our new design;

FIG. 2 is a front view thereof;

FIG. 3 is a back view thereof;

FIG. 4 is a right side view thereof;

FIG. 5 is a left side view thereof;

FIG. 6 is a top plan view thereof;

FIG. 7 is a bottom plan view thereof;

FIG. 8 is a front perspective view with front panels removed and illustrating railings in an engaged position in accordance with our new design;

FIG. 9 is a front perspective view with the front panels removed and illustrating railings in an extended position in accordance with our new design;

FIG. 10 is a front perspective view of a compressor enclosure in accordance with a second embodiment;

FIG. 11 is a front perspective view with front panels removed and illustrating railings in an engaged position in accordance with the second embodiment; and,

FIG. 12 is a front perspective view with the front panels removed and illustrating railings in an extended position in accordance with the second embodiment.

Any broken lines present in the drawings are for illustrative purposes only and form no part of the design to be patented.
